CHARLES H. HALL, OF SMITH'S FERRY, PENNSYLVANIA.

Letters Patent No. 86,535, dated February 2, 1869.

IMPROVEMENT IN DISTILLING HYDROCARBON-OILS.

The Schedule referred to in these Letters Patent and making part of the same.

To all whom it may concern:

Be it known that I, CHARLES H. HALL, of Smith's Ferry, in the county of Beaver, and State of Pennsylvania, have invented a new and useful Improvement in Distillation of Hydrocarbon-Oils and other liquids; and I do hereby declare the following to be a full, clear, and exact description thereof, reference being had to the accompanying drawing, making a part of this specification, which is a side elevation of an oil-still, partly in section, and illustrative of my improvement.

The nature of my invention consists in distilling hydrocarbon-oils or other distillable liquids by steam under pressure, and in the construction of apparatus therefor.

To enable others skilled in the art to make and use my invention, I will proceed to describe its construction and manner of use and operation.

a is a still, of any ordinary or known construction, which is placed on or in any suitable foundation or support.

b is a steam-pipe, leading from any suitable form of steam-generator, fitted with a valve, *b'*, and either opening directly into the still, at its lower part, or extending along through it any desirable distance, with small apertures, *c*, in any desirable number.

From the upper part of the still, a vapor-pipe, *d*, extends to the condensing-apparatus, which latter may be of any known construction.

The vapor-pipe *d* has a throttle or other like valve, *e*, of any convenient form, such that, by it the flow of vapor from the still *a* may be regulated or entirely cut off.

In using my improved process, I fill the still, or stills, if more than one is used, as full as may be desired—usually nearly full. Having closed the valve *e* of the vapor-pipe *d*, I open the steam-valve *b'* of the steam-pipe *b*, and through it admit into the body of oil in the still *a*, a flow of steam, either common or superheated, as may be preferred. This steam passes from the pipe *b*, either through its open end, or through the aperture *c*. The steam mixing with the oil, rapidly raises it to the vaporizing-point or temperature, and at the same time, as the steam accumulates in the still, it creates a pressure on the oil.

By an ordinary steam-gauge attached to the still, and communicating with the steam and vapor-space, the amount of the pressure is easily ascertained. Practically, I find that a high pressure is best.

When the pressure is up to, say from ninety to ninety-five pounds per square inch, though I do not wish to limit myself to these figures, I gradually open the valve or throttle *e* in the vapor-pipe *d*, and adjust and keep it and the steam-valve *b'* at such point that, while the oily vapors and steam pass off to the condenser, the

desired pressure shall be kept up in the still by the inflow of steam. This pressure is kept up, greater or less, as may be preferred, during the continuance of the process of distillation.

When all but the residuum has been driven over, the vapor-valve *e* is closed, then the steam-valve *b'*, and the residuum is drawn off or blown out into a tank.

Distilling thus by steam, under pressure, seems practically to have the effect of securing a more perfect admixture of the steam and oil, or of bringing them into closer contact with each other, or both, the result, however, being a much more rapid distillation.

The product, when condensed, is perfectly white and deodorized, in consequence of no offensive gases being generated in the process.

By dispensing with the application of fire to the still, I avoid all destructive distillation, and all danger of explosion.

The residuum, instead of being of a tarry nature, is in the condition of a heavy oil, valuable for lubricating-purposes.

Practically, there is no loss, except from the solid impurities in the crude oil, which are best removed by allowing them to settle, and separating them as sediment.

This mode of distillation I use for distilling all distillable liquids to which it can be conveniently applied.

I am aware that oil has been distilled under atmospheric pressure, and also under a pressure secured by confining in the still the vapors generated by a fire-distillation; but such mode of distilling is liable to the objections ordinarily incident to fire-distillation, and also to the objection, that thereby the rapidity of distillation is greatly lessened. By the use of steam, I avoid the destructive effects of fire on the oil, and by an intimate admixture of hot steam and oil, render the distillation more rapid, even under pressure, than when it is carried on in the usual way. I hence do not claim distillation under pressure generally, but only when such pressure is brought about by the introduction of steam into the body of the oil, as above set forth.

What I claim as my invention, and desire to secure by Letters Patent, is—

Distilling hydrocarbon-oils and other distillable liquids by steam, under pressure, substantially as hereinbefore set forth.

In testimony whereof, I, the said CHARLES H. HALL, have hereunto set my hand.

CHARLES H. HALL.
